UNITED STATES PATENT OFFICE.

JOHN P. COLEMAN, OF EDGEWOOD BOROUGH, PENNSYLVANIA, ASSIGNOR TO THE UNION SWITCH & SIGNAL COMPANY, OF SWISSVALE, PENNSYLVANIA, A CORPORATION OF PENNSYLVANIA.

RAILWAY-TRAFFIC-CONTROLLING APPARATUS.

Application filed August 24, 1923. Serial No. 659,115.

To all whom in may concern:

Be it known that I, JOHN P. COLEMAN, a citizen of the United States, residing at Edgewood Borough, in the county of Allegheny and State of Pennsylvania, have invented certain new and useful Improvements in Railway-Traffic-Controlling Apparatus, of which the following is a specification.

- 10 My invention relates to railway traffic controlling apparatus operated by fluid pressure, and particularly to apparatus for the control of traffic governing devices such as switches and the like.
- 15 Its object is to restore pressure to the apparatus should the device improperly assume a position inconsistent with safety and independently of its normal controlling mechanism, without the necessity as heretofore of unlocking the medium by which operation is normally accomplished.
- 20

Briefly the object is to restore by pressure to its original position a traffic controlling device that has shifted from causes extraneous to its normal controlling mechanism and without action of any parts of such mechanism.

I will describe one form of apparatus embodying my invention, and will then point out the novel features thereof in claims.

In the accompanying drawings, Fig. 1 is a view showing a railway switch having applied thereto, one form of operating mechanism embodying my invention. Fig. 2 is a sectional view of the valve apparatus shown in Fig. 1 and embodying my invention. Fig. 3 is a sectional view of a part of the valve mechanism along the line III-III of Fig. 2 looking in the direction of the arrows.

Similar reference characters refer to similar parts in each of the three views.

Referring first to Fig. 1, the reference character A designates a railway traffic controlling device which as here shown is a railway switch. This switch is operated by a fluid pressure motor B which motor is controlled by a main electro-magnetically controlled valve apparatus C and an auxiliary valve apparatus K.

The motor B, as here shown, comprises a cylinder 61 and a piston 62 operable therein. The piston 62 is operatively connected with the movable rails of switch A through

the medium of some suitable form of switch mechanism, comprising, as here shown, a bar 2 moved longitudinally by the piston 62, an alligator jaw 3 operated by a stud 63 on the bar 2, and a bar 4 operatively connected with the alligator jaw and also connected with the switch rails.

Referring now to Figs. 2 and 3, the valve apparatus C comprises a valve body 5 provided with a valve chamber 10 in which is located a slide valve 12 which reciprocates in suitable guides on a valve seat 11. The valve seat 11 is provided with three ports 13, 14 and 15 of which port 13 communicates directly with atmosphere and ports 14 and 15 communicate respectively with the left hand and the right hand ends of cylinder 61 by means of pipes 14^a and 15^a as shown in Fig. 1. The slide valve 12 is of the usual D-valve type having a recess 18 so that when the valve is in one extreme position, as shown in Figs. 2 and 3, it connects the right hand end of cylinder 61 with atmosphere and the left hand end with valve chamber 10, whereas when the valve is in the other extreme position it connects the right hand end of cylinder 61 with chamber 10 and the left hand end with atmosphere.

The valve body 5 is provided with another chamber 21 to which fluid pressure, usually air, is constantly supplied from a suitable source through inlet 25. Fluid pressure is at times supplied from the chamber 21 to valve chamber 10 through a valve 22 which is biased to the closed position by a spring 23 and by the action of the fluid pressure in chamber 21 on the back of this valve. The valve 22 is provided with a stem 24 which extends into valve chamber 10 and by means of which the valve may be opened at times as will hereinafter be explained.

The valve body 5 is provided with a cylinder 33 in which a piston 35 is adapted to reciprocate. Fluid pressure is supplied to the outer end of cylinder 33 from chamber 21 through ports 27 and 27^a and the supply is controlled by a valve device 29 which in turn is governed by an electro-magnet 30, hereinafter termed the "lock magnet." The valve device 29 connects port 27^a and hence cylinder 33 with atmosphere through opening 31, or with chamber 21 through port 27 according as the lock magnet 30 is de-en-

2
ergized or energized, respectively. Piston 35 is provided with a piston rod 35^a which passes through a cylindrical opening in the valve body 5 and into chamber 10 where it is operatively connected with a reciprocable plate 39 by means of a button 40 on the end of the piston rod 35^a and a jaw formed in the end of the plate. This plate 39 moves transversely to the direction of movement of the slide valve 12 and performs two functions, viz, to operate valve 22 and to mechanically lock slide valve 12.

Considering the locking function first, the upper surface of the slide valve is provided with three spaced transverse lugs 41, 42 and 43, thus providing slots into which passes a tongue 16 formed on the under side of plate 39. When the slide valve is in either extreme position the tongue 16 may pass into one or the other of the slots on the valve and so lock the valve in the position which it occupies, as shown best in Fig. 3. When, however, the piston 35 is moved by the admission of fluid pressure to cylinder 33, it moves plate 39 so that the tongue 16 is withdrawn from the slots in the slide valve whereupon the valve is free to be reversed. The other function of this plate, namely, the opening of valve 22, is performed by the same movement of this plate by the piston 35, and is accomplished merely through the engagement of the stem 24 by the end of the plate 39.

When the lock magnet 30 is de-energized so that the outer end of cylinder 33 is connected with atmosphere through port 27^a and port 31, the action of fluid pressure in chamber 10 on piston rod 35^a moves the piston 35 outwardly and the button 40 in turn moves plate 39 into the locking position, thus allowing valve 22 to seat. This movement is assisted by the action of spring 23 on valve 22 and so on plate 39. The action of spring 23 and fluid pressure in chamber 21 then holds valve 22 in the closed position and plate 39 in the locking position and so prevents accidental shifting of slide valve 12. The area of piston 35 is such however, that when fluid pressure is admitted against it through port 27^a by the energization of magnet 30, this pressure overbalances the combined forces of spring 23 and air pressure acting on valve 22 so that plate 39 is then moved to the unlock position, thus admitting fluid pressure to chamber 10. Plate 39 and valve 22 are restored to normal again upon the subsequent release of pressure from piston 35, by action of the pressure in chamber 10 against the smaller area of that piston designated as 35^a which allows the valve 22 to again seat.

The slide valve 12 is reciprocated by a fluid pressure motor device constructed as follows: In the valve body 5 are two axially

aligned cylinders 44 and 45 in which are located pistons 46 and 46^a, respectively. Rigidly, connected with piston 46 is a rod 47 and with piston 46^a a similar rod 48, which rods pass through suitable stuffing boxes in the valve body and abut against ends of the slide valve 12. It will be clear, therefore, that when the slide valve is unlocked, it may be reciprocated by supplying fluid pressure alternately to cylinders 44 and 45. The supply of fluid pressure for these cylinders is preferably taken from chamber 10. Cylinder 44 is connected with this chamber by ports 49 and 49^a, and the supply of fluid pressure to this cylinder is controlled by a valve device 53 which is in turn governed by an electro-magnet 51. Similarly, cylinder 45 is supplied by ports 50 and 50^a and the supply is controlled by a valve device 54 governed by an electromagnet 52. The arrangement of each valve device 53 and 54, and its corresponding magnet, is such that when the magnet is de-energized the corresponding cylinder is connected with atmosphere through a port 17 or 17^a, respectively, and that when the magnet is energized the corresponding cylinder is disconnected from atmosphere and is connected with valve chamber 10.

Referring now to Fig. 1, I have here shown one form and arrangement of circuits and conductors for the control of the valve device shown in Figs. 2 and 3. The electromagnets 30, 51 and 52 are governed by a contact 57 operated by a manually operable lever 56, which lever may be one of a plurality of such levers contained in an interlocking machine. It is understood that in practice suitable indication apparatus would be employed for controlling movements of the lever 56 in accordance with movement of the switch A, but in this view I have omitted the indication apparatus for purposes of simplicity and as not forming part of the present invention.

When the switch A occupies the position in which it is shown in Fig. 1, (which position I will herein term the normal position), and the contact 57 occupies the corresponding extreme position of its stroke in engagement with plate 57^a as shown in full lines in Fig. 1, magnet 51 (the "normal" magnet) is energized from battery 64, and the other two magnets are de-energized. The circuits for these magnets will be obvious from the drawing and consequently need not be traced in detail. Magnet 51 being energized, cylinder 44 is connected with valve chamber 10 by valve 53, but fluid pressure is not supplied to this cylinder because valve 22 between chambers 21 and 10 is closed, due to the fact that the lock magnet 30 is de-energized. The reverse magnet 52 is of course de-energized. The slide valve 12 is locked in its extreme right hand

position, and fluid pressure is cut off from valve chamber 10 and from all parts of the apparatus except chamber 21 and the port 27.

When it is desired to move the switch A to the other position (the "reverse" position), the manual lever 56 is swung to the right through a portion of its stroke until stopped by the indication apparatus in such position that the movable contact 57 is in engagement with both plates 57^a and 57^b. During this movement of the lever the circuit for lock magnet 30 is first closed at contact 57^c, and then the circuit for reverse magnet 52 is closed at contact 57^b, the circuit for normal magnet 51 being opened of course as contact 57 leaves plate 57^a. The energization of magnet 30 causes the admission of fluid pressure from chamber 21 to cylinder 33, thereby causing movement of piston 35 to unlock the slide valve 12 and open valve 22, as hereinbefore explained. The opening of valve 22 admits fluid pressure to chamber 10, and magnet 52 being energized, valve 54 admits fluid pressure from chamber 10 to cylinder 45 so that the slide valve 12 is shifted to the left. The movement is not impeded by pressure in cylinder 44 because the de-energization of magnet 51 causes this cylinder to be connected with atmosphere by valve 53. The reversal of slide valve 12 causes the admission of fluid pressure to the right hand end of cylinder 61, through ports 15 and 15^a so that switch A is then moved to the reverse position through the medium of the switch operating mechanism. When the movement of the switch is complete and the switch has been properly locked, the lever 56 in the interlocking machine is released by the indication apparatus not shown, and its movement to the right may be completed, thus opening the circuit for lock magnet 30. The de-energization of the lock magnet 30 causes cylinder 33 to be disconnected from the source of fluid pressure and opened to atmosphere, whereupon valve 22 becomes closed and the slide valve 12 locked in its extreme left hand position. All parts of the apparatus are thus disconnected from the source of fluid pressure except chamber 21 and port 27.

The operation of the apparatus for movement of switch A from its reverse to its normal position is similar to the operation just explained.

The valve apparatus K shown in detail in Fig. 2 comprises a valve body 70 provided with a chamber 82. Communicating with this chamber is a socket 71 adapted to receive a reciprocable plunger 72 operatively connected with the switch mechanism through the medium of bar 2. The valve body 70 is also provided with a chamber 76 which is constantly supplied with fluid pressure from a suitable source, not shown in the

drawing, through pipe 25. In practice, pipes 25 and 25^a would usually be connected to the same source of fluid pressure. Fluid pressure is at times admitted from chamber 76 to chamber 10 of valve apparatus C by means of port 77 and pipe 81. This supply is controlled by a valve device 73 operatively connected with a stem 73^a projecting into chamber 82 and provided at its free end with a roller 80 adapted to engage the surface of plunger 72. This plunger is provided with two spaced depressions 72^a and 72^b so disposed that when the switch A is locked in the normal position, as shown in the drawing, roller 80 on valve stem 73^a enters depression 72^b, and when the switch is locked in its reversed position, roller 80 enters depression 72^a. If, however, the switch occupies any except its two extreme positions and is not effectively locked the roller 80 engages the surface of plunger 2. The valve 73 is constantly urged toward plunger 72 by a spring 100. When the roller 80 occupies either depression 72^a or 72^b, valve 73 is closed but when roller 80 is moved out of these depressions by movement of plunger 72, valve 73 is opened and fluid pressure is admitted to chamber 10. A check valve 78 is arranged to prevent the escape of fluid pressure from pipe 81 back into the valve K during preliminary unlocking of the valve 41 by magnet 30 and piston 35. This valve is biased to its closed position by means of a spring 79.

If switch A has been set and locked in one of its extreme positions such as its normal position, as explained hereinbefore, plunger 72 will occupy the position shown in the drawing. Under these conditions roller 80 is seated in depression 72^b, valve 73 is closed and fluid pressure is cut off from all parts of valve K except chamber 76. If now, the switch A is displaced from its proper position by some means other than proper manipulation of lever 56 in the interlocking machine, as for example by malicious tampering, the corresponding movement of plunger 72 displaces roller 80 and causes valve 73 to open, thus admitting fluid pressure to chamber 10. Slide valve 12 being in its normal position, fluid pressure is therefore applied to the left hand end of cylinder 61 thus positively restoring the switch to its normal position, whereupon valve 73 is again closed and fluid pressure is disconnected from chamber 10.

Operation of the apparatus when the switch is set and locked in its reverse position is similar to that just explained for the normal position except that roller 80 then enters depression 72^a.

One feature of the apparatus hereinbefore described is that if the switch is improperly operated it will be restored to its proper position without unlocking the valve ap-

paratus C, and this restoring operation will take effect automatically and without manipulation of lever 56.

Another feature of the invention is that

5 after the restoring means have operated to move the switch back into its proper position the fluid pressure employed for this is automatically arrested from further affecting the apparatus.

10 Although I have herein shown and described only one form of railway traffic controlling apparatus embodying my invention, it is understood that various changes and modifications may be made therein within 15 the scope of the appended claims, without departing from the spirit and scope of my invention.

Having thus described my invention, what I claim is:

20 1. In combination, a railway traffic controlling device, a fluid pressure motor for operating such device, a valve chamber, a valve operating in said chamber to control said motor, manually controlled means for 25 supplying fluid pressure to said chamber, and other means responsive to the position of said railway traffic controlling device for automatically supplying fluid pressure directly to said chamber.

30 2. In combination, a railway traffic controlling device, a fluid pressure motor for operating such device, manually controlled means for supplying fluid pressure to said motor, and other means responsive to the 35 condition of said device for automatically supplying fluid pressure directly to said motor.

35 3. In combination, a railway traffic controlling device, a motor for operating said device, manually controlled means for supplying operating energy to said motor, and other means controlled by the position of said device for independently supplying substantially the same amount of operating 40 energy to said motor.

45 4. In combination, a railway switch, a motor for moving said switch to normal and reverse positions, manually controlled means for supplying operating energy to said motor, and other means controlled by the position of said switch for independently supplying operating energy to said motor.

50 5. In combination, a railway traffic controlling device, a fluid pressure motor for operating said device, a chamber, means for supplying fluid pressure from said chamber to said motor, manually controlled means for disconnecting fluid pressure from said chamber, and other means responsive to the 55 condition of said device, for at times supplying fluid pressure directly to said chamber.

60 6. In combination, a railway traffic controlling device, a fluid pressure motor for operating such device, normal means for 65

supplying pressure to said motor, and other means responsive to the conditions of said device for independently supplying fluid pressure to said motor.

7. In combination, a railway traffic controlling device, a fluid pressure motor for operating such device, normal means for supplying fluid pressure to said motor, and a valve controlled by such device for independently supplying fluid pressure to said 75 motor.

8. In combination, a railway traffic controlling device, a fluid pressure motor for operating said device, electrically controlled means for supplying fluid pressure to said motor, and mechanical means governed by the position of said device for independently supplying fluid pressure to said motor.

9. In combination, a railway traffic controlling device, a motor for operating said device, normal means for supplying energy to said motor, and other means governed by the position of said device for independently supplying substantially the same amount of 90 energy to said motor.

10. In combination, a railway traffic controlling device, a fluid pressure motor for operating such device, means for supplying fluid pressure to said motor, a valve operated by such device for at times independently 95 supplying fluid pressure to said motor, and a check valve interposed between said valve and said motor.

11. In combination, a railway switch, a motor for moving said switch to normal and reverse positions, means including a manually operable lever having normal and reverse positions for controlling the supply of operating energy to said motor, and other means operating when said switch is moved 100 away from the position harmonizing with the position of said lever to supply operating energy independently to said motor to automatically restore the switch to the position harmonizing with said lever.

110 12. In combination, a railway traffic controlling device, a fluid pressure motor for operating said device, a source of fluid pressure, a chamber, means including a lever for controlling the supply of fluid pressure from 115 said source to said chamber, means for controlling the supply of fluid pressure from said chamber to said motor, and means responsive to the condition of said apparatus for independently supplying fluid pressure 120 to said chamber.

125 13. In combination, a railway traffic controlling device, a fluid pressure motor for operating said device, a source of fluid pressure, a chamber, means including a lever for controlling the supply of fluid pressure from said source to said chamber, means for controlling the supply of fluid pressure from said chamber to said motor, and a valve interposed between said chamber and said 130

source and arranged to be closed only when said device is in proper operative relation to its motor.

14. In combination, a railway traffic controlling device, a fluid pressure motor for operating said device, a source of fluid pressure, a chamber, means including a lever for controlling the supply of fluid pressure from said source to said chamber, means for controlling the supply of fluid pressure from said chamber to said motor, a valve inter-
- posed between said source and said chamber and provided with a stem terminating in a roller, and a plunger operatively connected with said device and having a depression so disposed that when such device is in its proper position said roller enters said depression thereby permitting closure of said valve. 15
- In testimony whereof I affix my signature. 20

JOHN P. COLEMAN.
